CHILD'S ROCKING TOY

Richard E. Cone, Franklin County, Ohio, assignor to The Delphos Bending Company, Delphos, Ohio

Filed Feb. 24, 1971, Ser. No. 118,586

Term of patent 3½ years

Int. Cl. D21—01

U.S. Cl. D34—15

FIG. 1

FIG. 2

FIG. 4

FIG. 3

FIG. 1 is a perspective view of a child's rocking toy showing my new design;

FIG. 2 is a top plan view on a slightly smaller scale;

FIG. 3 is a side elevational view; and

FIG. 4 is a front elevational view thereof.

I claim:

The ornamental design for a child's rocking toy, substantially as shown.
